COMBINED AIR AND WATER CONTROL FOR STOPERS

Matthew O'Farrell, Utica, N. Y., assignor to Chicago Pneumatic Tool Company, New York, N. Y., a corporation of New Jersey

Application January 15, 1954, Serial No. 404,298

6 Claims. (Cl. 121—10)

This invention relates to rock drills of the self-rotating stoper type and more particularly to a combined air and water control therefor.

In rock drills of the stoper type where it is necessary to carry the water into the hole being drilled and to the working part of the tool bit in order to remove the cuttings and air to prevent the cuttings from dropping into the chuck parts of the drill when the drill has ceased to operate, it has been customary to have two tubes extending through the drill parts, one for the water and one for the air, with one of the tubes within the other. This has necessitated tubes with thin walls in order to economize on space, and breakage of the tubes has frequently resulted. It is necessary at times of shut down of the drill to leave the drill in the hole being cut and if air is not substituted for the water when the tool is shut down the residual muck and cuttings will enter the front end of the machine through the opening in the drill cutting element with resultant injury to the drill parts.

It is accordingly one object of the invention to provide a stoper that may supply water and air to the hole being drilled without requiring two thin tubes and with but a single tube.

It is another object of the invention to provide a combined air and water control for rock drills of the stoper type wherein automatically as the throttle valve is turned to initiate the operation of the rock drill, water is supplied through the delivery tube and drill cutting element to the inner end of the hole being drilled and wherein automatically as the rock drill is cut down and the water turned off, compressed air is delivered to the working point of the tool bit to prevent the residual muck and cuttings from entering the front of the drill and thereby prevent the injury to the working parts of the rock drill, and wherein the air will be automatically shut off when the rock drill is started up again and the water supply again automatically directed to the inner end of the hole being drilled to clean the cuttings therefrom.

It is another object of the invention to provide a combined air and water control for the rock drills of the stoper type employing automatic change over water to air upon turning the throttle valve from the working to the "off" position a one way valve backed up by water pressure when the rock drill is operating to maintain an air seal and prevent the entrance of the air to the delivery tube at that time and at the same time to prevent water from reaching the throttle valve to set up corrosion therein, the check valve being held firmly against its seat by a spring and assisted by the water pressure in a rearward direction.

It is still another object of the invention to provide the combined air and water control for rock drills of the stoper type within the back head of the stoper providing a water valve operated by cam action of the air supply throttle valve and an air valve provided in a plug and in communication with the water passage, the air valve plug being substituted for the prior plug used for the

2

conventional two tube type stopers and wherein the air and water control forms a part of the back head and a unitary assemblage requiring merely the substitution of the back head assembly for the prior back head of the conventional type of stoper.

Other objects of the invention are to provide a combined air and water control for rock drills of stoper type wherein the control is embodied in the back head of the stoper, which is of simple construction, inexpensive to manufacture, has a minimum number of parts, compact and consumes little space, easy to assemble, little chance of breaking, durable, automatic and efficient in operation.

For other objects and a better understanding of the invention, reference may be had to the following detailed description taken in connection with the accompanying drawings, in which:

Figure 1 is an elevational view of the rock drill of stoper type embodying the combined air and water control of the present invention, the drill bit penetrating a partially drilled hole in a mine roof and with the feed leg supported on the mine floor;

Figs. 2a, 2b, 2c constitute a substantially full sectional view taken generally on line 2—2 of Fig. 1 with one view being a continuation of another, the Fig. 2a showing the operating mechanism for the cutting element with the tool bit extending therefrom and lying within the chuck parts of the drill, Fig. 2b showing the back head embodying the combined water and air control of the present invention and Fig. 2c showing the lower end of the feed leg mechanism;

Fig. 3 is an enlarged fragmentary elevational view of the stoper along the region of the back head and with portions of the back head housing broken away to show the air throttle valve;

Fig. 4 is an enlarged sectional view of the back assembly broken away to show the combined air and water control parts and the single water and air tube extending therefrom, the view being taken generally on the line 4—4 of Fig. 3, but with diagrammatic view of the operating handle therefor;

Fig. 5 is an end elevational view of the back head with portions broken away to show the interior of the water valve and the detent means for the throttle valve;

Fig. 6 is a fragmentary sectional view of the detent valve as viewed on line 6—6 of Fig. 5;

Fig. 7 is a fragmentary sectional view of water supply passage extending from the valve element to the delivery tube and as viewed on line 7—7 of Fig. 4.

Referring now particularly to Fig. 1, the general construction of the rock drill of the stoper type will be described. This stoper comprises a cylinder assembly 21, a back head 22, a front head structure 23 and a telescopic feed leg assembly 24, all of which are held in fixed axial relationship by through bolts 25 and 26 disposed in guide lugs on the opposite sides thereof and respectively tightened by nuts 25' and 26'. A chuck 27 extends from the front head structure 23 and receives and retains a rock cutting drill element 28 having a cutting head 29 that drills a hole 31 in rock 32 when the stoper is operated. Stoppers have particular use in mines for drilling holes in the roof of the mine opening for the accommodation of roof bolts. The feed leg structure 24 has a cylinder 34 and a feed piston joint 35 engageable with floor 36 of the mine opening and operates automatically to feed the rock cutting drill element 28 into the rock 32 as the cutting action is effected. A holding handle structure 37 extends from one side of the cylinder structure 21.

The back head 22 has a throttle handle 38 extending from one side thereof and an air inlet swivel 39 at the opposite side thereof to which a hose 40 is connected

to deliver operating air under pressure to the stoper. At the rear of the back head there is connected a water inlet swivel 41 and a water throttle valve 42 to which a water hose 43 is connected for supplying the stoper with water. The cylinder assembly 21 has an oil plug 44 that is removable to supply the stoper with lubricating oil.

The prime difference in the use of the present invention over the conventional stoper lies in the single tube for the delivery of water and air and in the manner that water and air are controlled in the back head. A new back head is substituted for the conventional back head. The arrangement of the conventional inner operating parts will now be described, with reference particularly to Figs. 2a, 2b and 2c and later the description will be directed to the novel backhead construction.

Forwardly of the back head 22 are the cylinder structure 21 and the front head assembly 23. The parts therein are operated in the usual manner. Within the rear end of the cylinder structure 21 is a valve mechanism 45 for generally causing reciprocatory movement of a driving piston 46. This valve mechanism generally includes a valve guide bushing 47, Fig. 2b, a valve case 48, and a valve element 49 operable between the bushing and valve case.

Through this valve mechanism 45 extends a rifle bar 50 that is worked through a rifle nut 51 carried on piston 46 that is reciprocated within the cylinder 21. The rear end of the rifle bar is enlarged at 52 and carries pawls, not shown and this enlargement is rotated in one direction within a ratchet ring 54. A ratchet ring spacer 55 is disposed within the cylinder in the rear of the ratchet ring.

The piston 46 has splines 56 that extend through a chuck rotation nut 57 secured to anvil block sleeve 58 that extends through the front head 23 and connects with chuck 27. This anvil block sleeve carries an anvil block or hammer 59 that is hammered against rock drill element 28 to effect the cutting action in the hole being drilled. Rotation of the anvil block sleeve, the chuck and the drill element is effected upon the reciprocation of the piston 46 in the conventional manner by the rifle bar 50. The holding handle 37 is held in an opening 60 in an upstanding boss 61 and controls the exhaust air, but forms no part of the present invention.

In accordance with the present invention, there is provided only a single tube 63 instead of the usual two thin concentric tubes, which serve to deliver alternately water and air to the hole 31 being drilled in the mine roof. This tube 63 extends from the back head 22 through the ratchet spacer 55, the rifle bar 50, piston 46, the anvil block 59 and into central opening 64 in the rock drill element 28 so that either air or water is conducted by way of central opening 64 to the cutting head 29 of the rock drill element 28.

The feed leg structure 24 is fixed to the end of the back head 22 and the piston point 35 that engages with the ground is threaded into the lower end of a feed piston structure 66, Fig. 2c; the piston structure 66 has on its upper end an assembly of leather cups 67 and spacers 68, 69 and 70 all of which are held against a shoulder 71 on the piston 66 by a feed piston nut 72 that lies within a feed cylinder bushing 73 that secures the feed leg to the rear end of the back head 22.

The description will now be made to the back head construction wherein the invention lies. The throttle handle 38 is connected to a hollow throttle valve 75 by a spline 76, a lock washer 77 and a nut 78 whereby turning movement of the throttle valve may be effected, Fig. 3. The throttle valve 75 has an enlarged diameter portion 79 that is shouldered against the opposite end of throttle valve opening 75'. Air inlet swivel 39 is held in axial relationship with the throttle valve opening 75' by a swivel nut 80 and serves to conduct air under pressure to the interior of the throttle valve 75. The throttle valve 75 has a port 81 through which air is delivered

to air passage 82 in the back head, when the throttle handle 38 is moved to the forward position, Fig. 2b. Air is thus delivered under pressure through the ratchet ring spacer 55 and about the rifle bar enlargement 52 to the valve mechanism 45 to effect the reciprocating of the piston 46. The forward end of the back head 24 has an annular groove 83 by which air will be conducted to a rearwardly extending through passage 84 in the back head and to actuate the piston structure 66 of the feed leg mechanism 24.

Water, as stated above, is delivered to water inlet swivel 41 that is fixed in a threaded opening 85 located in rear of the throttle valve and is closed at the bottom end except for delivery passage 86, Figs. 4 and 5, that delivers water to the lower end of a water valve chamber 87 on one side of the back head and under a flat camming surface 88 on the throttle valve 75 that is engaged by a rounded upper end 89 of a valve element 90 operable within the valve chamber 87, Fig. 6. This valve element 90 has a conical portion 91 that engages a seat 92 in the chamber 87. This valve element 90 is normally held upwardly by a compression spring 93 and a plug 94 in an open end of the chamber 87 and has a reduced diameter portion 95 to allow water to pass to a passage 96 to a threaded counterbore or central opening 97 in the back head 22 and more particularly to the inner end of the opening into which a flanged end 98 of the tube 63 extends (Fig. 7). A sealing ring 99 surrounds the tube 63 forwardly of the enlarged head 98. The enlarged head 98 has four radially extending holes 100 which deliver the water to the center of the tube for delivery of water to the drill element 28. Rearwardly of the enlarged head 98 is a sleeve extension 101 through which water can pass rearwardly into the interior of a ball valve plug 102 threaded into the threaded opening 97.

This plug 102 has a ball seat 103 that is engaged by a ball element 104. The compression spring 105 acts against the ball valve element 104 to maintain it upon its seat. The spring 105 is held in place by a threaded end plug 106 having a hole therein communicating with the extension sleeve portion 101 of the tube 63. A large rubber cylindrical seal 107 surrounds the extension 101 and prevents leakage of water past the plug 102. When the valve element 75 is in operative position (Fig. 2b) air is being delivered to the valve mechanism 45 for operating the drill and the feed leg mechanism, the water is automatically directed to the tube 63 as the throttle handle 38 is moved forward to the "on" position.

The ball valve element 104 is then placed under pressure by the water and is retained on its seat 103 so that no water can pass the seat rearwardly to an air passage 109 that extends to the throttle valve 75. This ball valve element will thus keep the water out of throttle valve and prevent the corrosion thereof. Water is accordingly at this time delivered to the cutting drill element when the drill is running upwardly into the hole being drilled to thereby remove the cuttings therefrom.

As soon as the lever 38 is removed in the reverse direction to the "off" position, the stoper is stopped and air must be supplied to the inner end of the opening to prevent residual muck and cuttings from entering the drill element and the front end of the stoper. This air replaces the water so that the stoper can be left in place without loss of water or an undue wet mess in the bottom of the mine.

The throttle valve 75 has a small port 110, Figs. 3 and 4, that registers with the opening 109 so that air under pressure is delivered to radially extending passages 111 in the plug 102 that will lift the ball valve 104 from its seat and allow for the passage of air through the center of the plug 102 and plug 106 and the tube 63. The air will thus move through the tube 63 to the inner end of the hole 31 being drilled in the rock.

On the opposite side of the back head 22 and actuated by the enlargement 79 of the throttle valve 75 is a detent

plunger 113 that is urged toward circumferentially spaced holes 114 in the enlargement 79 by pressure detent spring 115 backed up by threaded plug 116, Fig. 5. By this means the throttle valve is held in its "on" and "off" positions.

It should now be apparent that there has been provided a special back head construction adapted for use with but a single water and air delivery tube that extends forwardly through the internal parts of the stoper in order to deliver alternately water and air to the inner end of the hole being drilled in the rock. It should also be apparent that automatically as the operator moves the throttle handle 38 between the "on" and "off" positions, the water and air supply is automatically controlled. Immediately and automatically as the stoper is started, the water supply is delivered to the inner end of the hole and automatically as this stoper is stopped, the water supply is dispensed with and air is automatically delivered in its place.

While various changes may be made in the detail construction, it shall be understood that such changes shall be within the spirit and scope of the present invention as defined by the appended claims.

What is claimed is:

1. In a rock drill of the stoper type including air powered means for driving a drill steel, a rotatable throttle valve controlling a source of pressurized air to the air powered means, and an open ended delivery tube for conduction of fluid to a channel through the drill steel, a fluid control arrangement including a water control valve actuatable upon rotation of the throttle valve to a first position to allow a flow of water to the delivery tube, the throttle valve in said first position providing communication of the air source with the air powered means, and a check valve disposed between an open end of the delivery tube and a passage leading to the throttle valve and arranged to prevent flow of water from the delivery tube to the throttle valve, the throttle valve being adapted when rotated to a second position to close off communication of the air source with the air powered means, to disable while being so rotated operation of the water control valve so as to shut off flow of water to the delivery tube, and to communicate when in its second position the source of pressurized air with the said passage so as to effect unseating of the check valve and pressurized air flow to the delivery tube.

2. In a rock drill including a backhead and having a rotatable throttle valve arranged in a throttle valve chamber formed in the backhead and a delivery tube for conduction of fluid to a drill steel, a fluid control arrangement including, water inlet means arranged in the backhead and a first passageway which leads from the water inlet means to a water valve chamber disposed in the backhead, a check valve assembly positioned in one end of a counterbore in the backhead the other end

of the counterbore being adapted for connection by a second passageway to the water valve chamber, said counterbore being adapted to receive an open end of the delivery tube, a valve element in the water valve chamber, 10 5 a third passageway for conduction of pressurized air from the throttle valve chamber to the check valve for passage therethrough to the counterbore, the check valve normally blocking the third passageway off from the counterbore to prevent passage of water into the third passageway, and cam means upon the throttle valve adapted to move the valve element when the throttle valve is in a first position so that water may flow from the water valve chamber into the second passageway, and being further adapted when the throttle valve is in a second position to allow the valve element to stop water flow from the water valve chamber into the second passageway and to allow flow of pressurized air into the third passageway.

3. In a rock drill according to claim 2, wherein a valve seat is arranged in the water valve chamber, and a spring means is adapted to urge the valve element toward seated engagement on the valve seat to prevent flow of water from the water valve chamber into the second passageway.

4. In a rock drill according to claim 3, wherein the check valve assembly has a valve element which is normally maintained in seated position by means of a compression spring and which is unseated by action of the pressurized air when the throttle valve is in second position.

5. In a rock drill according to claim 4, wherein a spring loaded detent pin is arranged in the backhead to selectively engage detents upon the throttle valve to maintain the throttle valve in set positions of rotation.

6. In a rock drill of the character described including a hollow drill steel, air powered means for driving the drill steel, and fluid delivery means communicating with the hollow drill steel; a check valve; and control means for effecting in a first operation flow of pressurized air to the air powered means and flow of water through the delivery means to the hollow drill steel, and effecting in a second operation shut-off of pressurized air to the air powered means, stoppage of water flow through the delivery means and flow of pressurized air through the check valve to the fluid delivery means, the check valve being effective during the first operation of the control means to block flow of water from the delivery means to the control means.
